UNITED STATES PATENT OFFICE.

ARTHUR L. WADDELL, OF CHICAGO, ILLINOIS.

GRINDING-GAGE.

1,149,311.

Specification of Letters Patent. Patented Aug. 10, 1915.

Application filed September 17, 1914. Serial No. 862,155.

To all whom it may concern:

Be it known that I, ARTHUR L. WADDELL, a citizen of the United States, residing at Chicago, in the county of Cook and State 5 of Illinois, have invented certain new and useful Improvements in Grinding-Gages, of which the following is a specification.

My invention relates generally to devices for gaging the sharpening of tools having 10 beveled edges, but particularly to devices for gaging the edging of scissors, chisels plane-bits, etc., and has for its object the production of an article of manufacture that will be, at once, simple, light, cheap 15 and easy of construction, and that will hold such a tool in such a position on a plane-surfaced whet-stone or other suitable abrading medium as to enable the operator to give it a uniform edge at a given and uniform 20 angle. I attain this object by a device which consists of the combination of a holder for gripping the tool to be sharpened, a binding-screw or nut for securing the tool in said holder, a gage-bar having one end at 25 attached to said holder and the other so constructed as to slide easily on a table or other smooth plane surface on which the whet-stone or other suitable abrading medium may be resting, and at the same time hold 30 the rest of the device free of said surface and medium and an adjustment-joint at some point along said gage-bar, or at the point or points of its attachment to said holder, for the purpose of adjusting the 35 device to the bevel of the edge to be sharpened.

Referring to the drawing, Figure 1, represents a side elevation showing the device in approximately full size, and showing 40 cross-sectionally the blade of a pair of scissors or shears in place in the holder and resting on a whet-stone, the latter and the extreme end of the gage-bar resting on a table or other smooth, plane, horizontal surface. Fig. 2. represents a front elevation of 45 the same except that the pair of scissors is shown in full, or nearly so. Fig. 3. represents the side elevation of a modification of the device, reduced to about one half its 50 actual size, and holding a plane-bit in position on a whet-stone and ready to be agitated under pressure by the hand; while Fig. 4. is a view of the modification from beneath.

55 The same reference characters refer to the

same or similar parts throughout the various views respectively.

The device is made of steel or other suitable metal or material, and consists of the holder A, the gage-bar B, the binding or set-screw C, and the adjustment-joint D. The attached end of the gage-bar B, is provided with threads, and the binding-nut C, is screwed down into position thereon. This threaded end is then passed through a hole 60 in about the middle of the posterior mandible of the holder A, said hole being large enough to permit of its free sliding therein, and its tip is inserted into a smaller hole in a corresponding position in the anterior 65 mandible, where it is firmly riveted in place. The free end of the gage-bar B, is bent downward and otherwise suitably curved so as to rest and easily slide around on a table or other smooth plane surface, and at the 70 same time hold said holder and the intermediate portion of said bar free of said surface and any suitable whet-stone or other abrading medium resting thereon; while at or near the middle the gage-bar B, is pro- 75 vided with a hinge joint D, for the purpose of adjustment to the angle of the bevel of the tool to be sharpened, said joint being stiffened by a short bolt and wing-nut.

It will be observed that, when a blade of 80 a pair of scissors or shears is firmly gripped in the holder, as shown in Figs. 1. and 2., and the gage-bar is properly adjusted to the bevel of the blade, an operator can, by placing the blade on a suitable whet-stone 85 or other abrading medium lying at the edge of a table, or other smooth plane surface, and the free end of the gage-bar on the table or surface itself, actuate the whole under pressure of the hand with the effect 90 of giving to the blade a uniform edge at a uniform angle.

In the modified form, shown in Figs. 3. and 4., the holder E is in the form of an incomplete box with slots in its sides to permit of the insertion of a chisel or plane-bit, and a shorter slot in its top to permit a binding nut and screw G to be inserted and to slide back and forth therein, so that the same can always be set on the tool to be 100 sharpened at or about its middle longitudinal line. The gage-bar F, in this modification is double, both ends articulating with the holder E, and the adjustment is effected by wing-nuts H at the articulations. To 110

give stability to this modification, the gage-bar F, is so bent that its two limbs flare, and that it will rest on the table, or other plane surface in connection with which it is used, only at the angles, the entire contrivance resting on the whet-stone and table or other surface much after the manner of a tripod.

It is of course understood that other modifications, such as the omission of the adjustment-joint from the preferred form, or placing the binding nut at the extreme near end of the gage-bar and in front of the anterior mandible instead of back of the posterior mandible as shown in the preferred form, or using a pair of holders such as shown in the preferred form, turned on the side with mandibles facing each other, for holding chisels, plane-bits, etc., might be resorted to, but without departing from the principle, scope and spirit of my invention, or resulting in anything but substantial equivalents; and such modifications are herein expressly included.

Having described my invention, I claim:

1. In a grinding-gage, a one-piece adjustable blade-holder, a binding-screw co-operating with and controlling same, and an adjustable gage-bar attached thereto, and bent to slide easily on a smooth plane surface supporting a suitable abrading medium, and hold the rest of the device

free of said surface and medium when, with blade in place, the same is actuated thereon under pressure by the hand.

35

2. In a grinding-gage, the combination of a one-piece recurved blade-holder with a gage-bar bearing threads and carrying a binding-nut at its attached end, and having its free end bent to slide easily on a smooth plane surface supporting a suitable abrading medium, and hold the rest of the device free of said surface and medium when, with blade in place, the same is actuated thereon under pressure by the hand.

40

3. In a grinding-gage, the combination of a one-piece adjustable blade-holding member bent to form a pair of mandibles for securing the blade to be sharpened, with a gage-bar bearing threads and carrying a binding-nut operating thereon at one end, and attached thereto to one of said mandibles, while passing loosely through the other, and having its free end bent to slide easily on a smooth plane surface supporting a suitable abrading medium, and hold the rest of the device free of said surface and medium when, with blade in place, the same is actuated thereon under pressure of the hand.
